CLAIM

The ornamental design for a foldable sink table, as shown and described.

DESCRIPTION

FIG. 1 is a perspective view taken from the top, front and left side of a foldable sink table showing my new design;

FIG. 2 is a left side elevational view thereof;

FIG. 3 is a front elevational view thereof;

FIG. 4 is a rear elevational view thereof;

FIG. 5 is a bottom plan view thereof;

FIG. 6 is a right side elevational view thereof;

FIG. 7 is a top plan view thereof;

FIG. 8 is a front elevational view thereof, depicting a portion stored in folded position;

FIG. 9 is a further front elevational view thereof, depicting another portion stored in folded position; and,

FIG. 10 is yet a further front elevational view thereof, depicting all portions stored in a folded position.
